UNITED STATES PATENT OFFICE.

CHARLES E. MAUD, OF MONTEREY, CALIFORNIA.

EXPLOSIVE-ENGINE.

No. 856,847.

Specification of Letters Patent.

Patented June 11, 1907.

Application filed January 30, 1907. Serial No. 354,884.

To all whom it may concern:

Be it known that I, CHARLES E. MAUD, a citizen of the United States, residing at Monterey, in the county of Monterey and State 5 of California, have invented a new and useful Explosive-Engine, of which the following is a specification.

This invention has reference to improvements in explosive engines, and it is directed 10 more particularly to the type of engines known as two-cycle engines.

The object of the present invention is to provide a deflector for the burned gases and for the fresh air at the exhaust end of the 15 stroke, whereby the incoming fresh air will thoroughly scavenge the cylinder of all burned gases, and thus improve the new explosive mixture.

The invention also has for an object to 20 provide a means whereby the explosion is effected similar to and with all the advantages of an auxiliary explosion chamber such as has been employed with the hot-ball type of ignition.

To this end the invention consists in a deflector of frusto-conical shape carried by the 25 explosion end of the engine, for receiving the incoming fresh air through suitable air-ports and directing it centrally to the explosion 30 chamber and in a direction toward the rear thereof. The rear end of the explosion chamber is formed to divert the incoming air-stream along the outer walls of the explosion chamber and to the exhaust port.

By forming the rear end of the explosion 35 chamber into an inwardly-directed cone so as to be coincident with or enter the rear of the deflector dome, and by locating the igniter at the apex of this inwardly-projecting cone-shaped end of the explosion chamber cylinder, the explosion takes place partially within the deflector and the explosive mixture 40 therefore burns with greater efficiency than it otherwise would.

The invention will be fully understood 45 from the following description taken in connection with the accompanying drawings forming part of this specification, in which,—

Figure 1 is a longitudinal section of the 50 working cylinder and crank case of a two-cycle engine made in accordance with my invention, with the piston in position for the forward power stroke; and Fig. 2 is a similar view, with the piston at the completion of 55 the power stroke, with the exhaust port and the air inlet ports open.

Referring to the drawings, there is shown a cylinder 1 in which plays the piston 2 of an explosive engine, and at the front of the cylinder 1 there is provided a crank case 3 of 60 usual type which, although not so showing, is to be understood to be in communication with the external air. Into this crank case extends a pitman 4 connected to the crank 5 carried by a shaft 6 in the usual manner. 65 The shaft 6 has bearings in the journal boxes 7 which, if desired, may terminate in packing glands 8.

It will be understood that in the drawings no attempt has been made to show the engine 70 in commercial form, the parts, as shown, being largely diagrammatic and all extraneous devices, including the usual cooling jackets, having been omitted.

The rear end 9 of the cylinder is curved and 75 has centrally located therein an inward cone-shaped projection 10 in the apex of which is located a sparking-plug 11, or other igniting device.

The rear end of the head of the piston has 80 formed thereon a cone-shaped projection 12, the walls of which are curved inwardly but may, if desired, be made in the shape of a true-cone with straight walls.

Carried by the rear end of the cylinder by 85 means of bridge pieces 13 is a frusto-conical deflector 14 having its walls also curved inwardly and terminating in a mouth 15 of considerably less diameter than the diameter of the interior of the cylinder 1. In the 90 drawings but two bridge pieces 13 are shown but it will be understood that as many of these bridge pieces will be used as may be necessary. The base of the deflector 14 makes contact around its periphery with the 95 inner walls of the cylinder 1, but because of the bridge pieces 13 there is a broken annular space 16 left between the head of the cylinder and the deflector 14.

Located at a proper point to be normally 100 closed by the piston and to be opened at the proper time in the cycle of operation are exhaust ports 17—17, preferably two or more in number, and connected together through a conduit 18 extending around the 105 cylinder, and these ports communicate freely with an exhaust pipe 19 through which the burned gases are conveyed away.

Located farther toward the front end of the cylinder and immediately adjacent to the 110 exhaust ports 17 are air-inlet ports 20, preferably two or more in number and, like the

exhaust ports, located on opposite sides of the cylinder, although not necessarily so. Leading to these air-inlet ports are conduits 21 in free communication at their front ends with the interior of the crank case 3, as is usual in the two-cycle type of explosive engines.

- Now, suppose the parts are in the position shown in Fig. 1 and a compressed charge of explosive mixture is behind the piston. A spark from the sparking-plug 11 will fire this charge and, because of the fact that the sparking-plug is partially contained within the deflector 14, the combustion will be slightly retarded and it will take an appreciable time for the explosion to be completed. In the meantime the piston is moving forward under the explosive action of the burned gases and ultimately the annular space 16 between the deflector 14 and the head of the piston will reach the exhaust ports 17 and the burned gases will find an exit through the open mouth 15 of the deflector 14 and through the exhaust ports 17. A still further forward movement of the piston will uncover the ports 17 to the gases exterior to the deflector 14, and finally the annular edge of the deflector 14, where it is in contact with the inner wall of the cylinder 1, will have passed the ports 17, as shown in Fig. 2, at which time the air-inlet ports 20 will be coincident with the annular space 16 between the deflector 14 and the head of the piston. The air which has been compressed during this operation in the usual manner in the crank case 3 now flows, under this pressure through the ports 20 into the interior of the deflector 14 and is expelled through the opening 15 directly backward against the rear wall of the cylinder 1. This rear wall having an inverted conical axial projection, the incoming compressed air escaping from the mouth 15 on reaching this rear wall will be diverted toward the walls of the cylinder 1 and in a forward direction and ultimately finds exit through the exhaust ports 17, very thoroughly driving before it the burned gases of the previously exploded charge and thus scavenging the cylinder in a very perfect manner.
- It will be understood that on the return movement of the piston a fresh charge of gas, or other suitable material for the purpose, will be introduced into the explosion chamber to be mixed with the air and compressed and exploded again in the usual manner.
- By my invention I avoid the formation of eddies within the explosion chamber which tend to form dead pockets of burned gases and to prevent the incoming rush of air from thoroughly clearing out the burned gases from the explosion chamber; this is due to the fact that the incoming air is projected rearwardly

approximately through the axis of the cylinder and then carried to the exterior walls thereof to flow, still under the impulse of the force of injection, in a forward direction toward the exit ports, so that a very much more thorough scavenging of the burned gases is accomplished than when the ordinary deflector plates usually used on two-cycle engines are employed. For this purpose the deflector plate 14 might be used alone, but the operation is made more efficient by the employment in connection with the deflector plate of the cone 12 having inwardly-curved walls whereby the space within the cone-shaped deflector is restricted so that the incoming air from the ports 20 will be more effectually guided to the opening 15 and the pressure maintained to this point, whereby the incoming air is projected as through a funnel, with force, directly rearward in approximately the direction of the axis of the explosion chamber.

I claim:

1. An explosive engine of the two-cycle type having a working cylinder provided with an axial, inward, cone-shaped projection on its rear wall and provided with air inlet ports opening into said cylinder at the extreme limit of the power stroke of the piston and with a free exhaust port adjacent to the air ports, and a power piston contained in said cylinder and provided with a hollow, frusto-conical air deflector carried by but spaced from the rear wall of the piston and coacting with the cone-shaped projection on the rear wall of the cylinder to direct a scavenging charge of compressed air from the air ports rearward to the cone-shaped rear wall of the cylinder and thence forward to the exhaust port.

2. In an explosive engine of the two-cycle type, a piston, a hollow air-deflector carried thereby, and means for igniting a charge in the path of said air-deflector and arranged to enter the same when the charge is compressed for firing.

3. In an explosive engine of the two-cycle type, a piston, a hollow air-deflector opening toward the rear, an explosion chamber having its rear wall provided with an inward axially-located cone-shaped projection, and an igniting device carried by said projection and arranged to enter the open end of the deflector.

In testimony that I claim the foregoing as my own, I have hereto affixed my signature in the presence of two witnesses.

CHARLES E. MAUD.
